(57) **CLAIM**

I claim, the ornamental design for a high pressure vacuum bottle, as shown and described.

DESCRIPTION

FIG. 1 is a front, top, right side perspective view of a high pressure vacuum bottle according to the new design;

FIG. 2 is a front side elevation view thereof;

FIG. 3 is a rear side elevation view thereof;

FIG. 4 is a left side elevation view thereof;

FIG. 5 is a right side elevation view thereof;

FIG. 6 is a top plan view thereof;

FIG. 7 is a bottom plan view thereof; and,

FIG. 8 is a front, bottom, left side perspective view thereof.

The broken lines in the drawings illustrate portions of the high pressure vacuum bottle which form no part of the claimed design.

The oblique lines in the figures show a translucent or transparent material.
